(57) **CLAIM**

The ornamental design for an apparatus for the preparation of food and drink, as shown and described.

DESCRIPTION

FIG. 1 is a top, right perspective view of the apparatus for the preparation of food and drink showing my new design; FIG. 2 is a bottom, left perspective view thereof; FIG. 3 is a front view thereof;

FIG. 4 is a right side view thereof;

FIG. 5 is a rear view thereof;

FIG. 6 is a left side view thereof;

FIG. 7 is a top view thereof;

FIG. 8 is a bottom view thereof;

FIG. 9 is a top, right perspective view of the apparatus for the preparation of food and drink shown in a second configuration with a removable insert removed;

FIG. 10 is a bottom, left perspective view thereof;

FIG. 11 is a front view thereof;

FIG. 12 is a right side view thereof;

FIG. 13 is a rear view thereof;

FIG. 14 is a left side view thereof;

FIG. 15 is a top view thereof;

FIG. 16 is a bottom view thereof;

FIG. 17 is a top, right perspective view of the apparatus for the preparation of food and drink shown in the second configuration of FIG. 9 with a removable insert removed and portions thereof shown in broken lines;

FIG. 18 is a bottom, left perspective view thereof;

FIG. 19 is a front view thereof;

FIG. 20 is a right side view thereof;

(Continued)

FIG. 21 is a rear view thereof;
 FIG. 22 is a left side view thereof;
 FIG. 23 is a top view thereof; and,
 FIG. 24 is a bottom view thereof.

The broken lines in FIGS. 17, 18, 19, 20, 21, 22 and 24 depict portions of the apparatus for the preparation of food and drink that form no part of claimed design.
